UNITED STATES PATENT OFFICE.

WALTER W. MACFARREN, OF PITTSBURGH, PENNSYLVANIA.

CHAIN HYDRAULIC MINING MACHINE.

Application filed November 3, 1915. Serial No. 59,377.

My invention relates to mining machines and more particularly to those used in bituminous coal, although my improved machine is in effect a tunnelling machine and 5 may be used to drive an entry or tunnel in any material which can be slotted by available cutters.

While my improved machine is primarily intended for entry driving it may also be 10 used for room work or as a longwall machine.

When driving an entry the machine would mine out the full height and width at one cut, when used in rooms or for longwall work the machine would mine the full height of the 15 coal (usually, not necessarily) and would take successive cuts of any desired width until the whole desired width was mined.

My improved machine is believed to embody entirely new principles for mining coal 20 or other comparatively soft minerals. These are, first, cutting two or more slots in the coal across the working place. Second, breaking down the lump between the slots by the use of hydraulic or other intense slow 25 acting pressure.

The design shown is intended for use in the Pittsburgh coal seam in which there occurs at a level usually below the middle of the seam, a pair of slate bands of a combined thickness 30 of about an inch.

By cutting out these bands and reducing them to slack or fine cuttings they are automatically separated from the lump coal, a process now having to be performed by hand.

The objects of my invention are to produce 35 a mining machine of reliable and durable construction which will produce a large tonnage of merchantable coal with a minimum proportion of slack and a minimum consumption of power and with minimum attention. To these ends I provide the various parts, one arrangement and combination of which is shown in the accompanying drawings in which:

Fig. 1 is a sectional side elevation of the machine in working position in a mine.

Fig. 2 is a plan view of the same partly in section on the line 2—2, Fig. 1 and with certain parts omitted.

Fig. 3 is a diagrammatic vertical cross section of the machine on the line 3—3, Figs. 50 1 and 2.

Fig. 4 is a diagrammatic front elevation of the machine on the line 4—4, Figs. 1 and 2.

Fig. 5 is a vertical cross section through 55 one of the hydraulic breakers on the line 5—5, Fig. 2.

Fig. 6 is a longitudinal vertical section of the line 6—6, Fig. 2, but showing a modified 60 form of breaker.

Fig. 7 is a diagram showing the operation of the machine when working in rooms.

Fig. 8 is a diagram of the hydraulic mechanism on the machine.

Fig. 9 is a plan view with the conveyer 65 mechanism and the cutting mechanism removed so as to show the main frame and the driving mechanism mounted thereon.

Fig. 10 is an enlarged vertical section showing the connection of adjusting screw 42 to 70 the lower cutter frame.

Fig. 11 is an enlarged sectional view showing the adjustable connection of the breaker bar to the middle cutter frame on the line 75 7—7 of Fig. 2.

Referring to the drawings I designate the main frame as a whole by A, the ground wheels as a whole by B, the upper chain frame as a whole by C, the middle chain frame as a whole by D, the lower chain frame as a 80 whole by E, the main adjusting screws as a whole by F, the hydraulic breakers as a whole by G and the hydraulic turntable as a whole by H.

The main frame A is composed of two outer 85 side pieces 1, two inner side pieces 2, a front cross piece 3, a middle cross beam 4, a rear cross piece 5, two motor supports 6, two front braces 7, two rear braces 8, and other less important members.

All the other parts of the machine are attached directly or indirectly to the main frame A, and the latter is supported and carried by the ground wheels B, of which there are eight.

The front ground wheels 9 are each carried by a short axle 10 mounted in bearings 11 on frame A. The second pair of ground wheels 12 are carried by a common axle 13 mounted in bearings 14 on frame A.

The third pair of ground wheels 15 are carried by an axle 16 mounted in similar bearings 17, and the fourth or rear pair of ground wheels 18 are carried by an axle 19 mounted in bearings 20 on frame A.

Mechanism is provided for driving the ground wheels at two speeds, to wit, a speed of about one hundred feet per minute, called

- the travel speed, and a speed of about six inches per minute, called the feed. Both drives are secured from a motor 21 mounted on the frame 1, and which is connected to the 5 axle 16 through a spur gear to give the travel speed and also through a worm gear to give the feed. As shown the motor armature pinion meshes with a spur gear 220 loose on axle 19, and which gear has integral therewith, or secured thereto, a pinion 221 which meshes with a spur gear 222 fastened on the transverse shaft 223. This latter shaft connects through spur gears 224 with the compound worm gear 225 which drives a worm wheel (not shown), loose on shaft 16 and which worm gear is provided with a clutch member 226. Shaft 223 also carries a spur pinion 227 meshing with spur gear 228, likewise loose on shaft 16 and provided with a 10 clutch member 229. Fastened on the shaft 16, between the clutch members 226 and 229 is a sliding clutch member 230, by means of which either the spur gear 228 or the worm drive 225 can be connected to shaft 16.
- 15 The axle 19 is driven by sprockets 22 and 23 and chain 24 from axle 16.
- 18 The axles 10 are similarly driven from axle 13 by sprockets 25 and 26 and chains 27.
- 21 A bevel gear 28 on axle 16 drives a bevel pinion 29 or a short longitudinal shaft 30.
- 24 A second bevel pinion 31 drives a second bevel gear 32 or axle 13. Thus all the axles are connected and all the ground wheels B are driven.
- 27 The slow speed is used to advance the chains to make their cuts and the fast speed to move the machine from place to place.
- 30 The lower chain 33 mounted on the chain frame E makes an undercut about 4" high and 14" deep.
- 33 The upper chain 34 mounted on the chain frame C makes an uppercut of the same dimensions but is advanced about a foot further into the coal.
- 36 The middle chain 35 mounted on the chain frame D makes a cut about 6" high and is advanced into the coal about 16" further than the upper chain 34 and 2'-4" further than the lower chain 33. These relations of the 40 several chains are permanent.
- 39 Between cut made by the upper chain 34 and the middle cut 37 a lump or projection 39 is left and between the middle cut 37 and the undercut 38 there is a corresponding lump 40.
- 43 In this particular design the middle chains 35 are not set at the middle of the height of the coal, but are located on the level of a pair of slate bands 41 so as to cut them out and separate them from the lump coal.
- 46 The lower chain frame E is adjustable vertically (upwards) for about 2" by means of the front and rear carrying screws 42 and 43. These screws extend through long bosses 44 and 45 on the frame A. The chain frame E is 50 also adjustable downwardly, for a small

amount and the path of the machine vertically is controlled by the adjustment of the chain frame E. Since the lower chain 33 cuts the floor on which the machine travels, when the lower cutting points of the chain 33 are in the same plane as the bottoms of the ground wheels B (or slightly above them to allow for sinking of the ground wheels below the plane of the floor) the machine travels forward in the plane of the wheel bottoms.

If now the chain frame E be lowered $\frac{1}{8}$ " (the chain cutting clearance for itself as it is lowered) the front end of machine will drop $\frac{1}{8}$ " as soon as the second pair of ground wheels 12 have dropped over this $\frac{1}{8}$ " step. When this occurs the chain 33 will be lowered with the ground wheels (since the two are rigidly connected) and a second downward step of $\frac{1}{8}$ " will be cut on the bottom and this action continued will produce a series of downward steps so that the machine would drop 1" in about 8 feet advance. The above relates to ground wheels 9 and 12.

Now since the rear strand of chain 33 passes across the machine just back of wheels 12 it will cut a corresponding series of steps for the ground wheels 15 and 18 and the machine will therefore drop practically parallel to its previous path.

When the chain frame E is raised slightly instead of lowered the machine will rise instead of fall. Since there are four screws 42 to 43 these may be used to level the chain frames C and E both sidewise and lengthwise. When it is desired to travel the machine from place to place the chain frame E may be raised about 2" by removing the collars 46 and tightening the nuts 47.

The height being mined may be regulated by vertically adjusting the upper chain frame C on the screws 42 and 43 by means of the nuts 48 and 49.

The chain frames C, D and E are all substantially rectangular in shape and have a sprocket at each corner.

The upper chain frame C carries idler sprockets at its outer corners and the sprockets 52 and 53 at its inner corners (see Fig. 3).

The arrangement is similar for chain frames D and E.

Referring to Figure 3 the bearings 54 and 55 are secured to the upper chain frame C and move vertically therewith. The bearings 56 and 57 are similarly secured to the chain frame E. The bearings 58, 59, 60 and 61 are secured to the main frame A.

The middle chains 35 are driven by a motor 62 at the right side of the machine and the top chains 34 and bottom chains 33 are driven by a motor 63 at the left side of the machine, and running in the opposite direction. At the front of the machine the top and bottom chains 34 and 33 cut from left to right and the middle chains 35 cut from right to left.

By this arrangement two desirable results are obtained,

First, the side thrust of one set of chains is balanced against that of the other set.

Second, the clean cuttings or slack from the upper cut 36 and the lower cut 38 is thrown to one side of the machine and the dirty or slate containing cuttings from the middle cut 37 is thrown to the opposite side of the machine, thus effecting an automatic separation of these products which is of advantage as it is done at practically no expense.

The motor 63 drives a countershaft 64 by means of spur gears 65 and 66, the shaft 64 being mounted in bearings 67 secured to frame A.

A bevel pinion 68 on shaft 64 drives a bevel gear 69 on a vertical shaft 70. The weight of shaft 70 is transferred to gear 69 by a collar 71 on shaft 70 and gear 69 rests on a thrust bearing 72 which in turn rests on bearing 58.

Shaft 70 drives sprocket 52 by a feather key 73 and also drives sprocket 74 by a feather key 95.

Sprocket 52 drives upper chain 34 and sprocket 74 drives lower chain 33.

A loose sleeve 75 mounted in bearings 58 and 59 surrounds shaft 70 and carries a pair of sprockets 76 for the middle chains 35, the weight of sleeve 75 being carried by a thrust bearing 77 resting on bearing 59. Bearings 54, 55, 56, 57, 58, 59, 60 and 61 are all provided with caps.

It will be noted that shaft 70 and sleeve 75 are entirely independent of each other so they may rotate in opposite directions.

From the motor 62 power is transmitted to a countershaft 78 by means of spur gears 79 and 80. A bevel pinion 81 on shaft 78 drives a bevel gear 82 on a sleeve 83. The sleeve 83 is supported in bearings 60 and 61 and provided with a carrying thrust bearing 84. A pair of sprockets 85 are mounted on sleeve 83 which drive the middle cutting chains 35.

The shaft 78 is mounted in bearings 86 and 87 secured to frame A.

The sprocket 53 is carried by the bearing 55 and the sprocket 88 is carried by the bearing 57. A shaft 89 extends through the sleeve 83 and engages loosely the sprockets 53 and 88, its function being merely to align the sprockets 53 and 88 and neutralize the twisting strains caused by the eccentric pull of the chains 34 and 33. A collar 90 on shaft 89 transfers the weight of the shaft to a thrust bearing 91 resting on bearing 60.

Referring to Fig. 1 the lower lump 40 is ready to be broken down. For this purpose a cast steel "breaker bar" 92 is carried on guides 93 secured to the middle chain frame D. The breaker bar 92 has a to and fro movement in the direction of the machine's travel of about 12", the same being actuated by a hydraulic "shifting cylinder" 94 formed in the front cross piece 3 of frame A. A piston 96 in

cylinder 94 actuates a hollow piston rod 97 connected to the breaker bar 92.

A number of cylindrical bores 98 are formed in breaker bar 92 (see Fig. 5). Within each bore 98 there are placed two cylindrical bushings 99 having screw threads 100 to secure them to bar 92 and flanges 101 to the screw threads.

The inner ends of bushings 99 have tapered ends 102 which bear on soft metal ring gaskets 103. Between the ends of bushings 99 a stop ring 104 is placed, the arrangement being such that when the threads 100 are screwed tight the flanges 101 are in close contact with the bar 92 and the stop ring 104 is loosely held between the ends of bushings 99. The gaskets 103 are clamped in the triangular space between bushings 99, bore 98 and stop ring 104 and make a pressure tight region between these parts.

Within each bushing 99 there is placed a plunger 105 having its individual cup leather 106 and retaining ring 107. Each plunger 105 has an external shoulder 108 which co-operates with internal shoulders 109 on the bushings 99 to limit the stroke of the plungers.

Pressure to force the plungers apart enters through a small passage 110 extending through the stop ring 104. To draw the plungers together after they have broken down the coal a helical spring 111 is used. This spring has threaded ends 112 screwed into small taper plugs 113 which are externally threaded and screwed into the ends of the plungers, the small square end 114 shown in dotted lines being then cut off.

When the plungers 105 with connected spring 111 and stop ring 104 are assembled and the upper bushing 99 is removed the above assembled parts can be placed in position in the bore 98 and the upper bushing 99 put in above them.

Fig. 6 shows a sectional elevation of a modified form of breaker cylinder the section being taken longitudinally of the breaker bar 92. In this modified form of breaker the plungers 183 of alternate cylinders operate from opposite sides of the breaker bar 92, one coming out of the top of the bar and the next one out of the bottom and so forth, the prime purpose being to reduce the height of cut necessary to contain the breakers.

While Fig. 6 shows the same height of cut and larger plungers than Fig. 5, for the same size plunger the cut would be less. The plungers in Fig. 5 (shown half size) are three inches in diameter and the cut 35 is six inches high. For the form of breaker shown in Fig. 6 a three inch diameter plunger would correspond to a four and one-half inch cut.

The plunger 183 is provided with a cup leather 184 and a retaining plug 186 therefor which is threaded and screwed into the bottom (or top) end of the plunger as shown at 187. Holes 188 are provided for a spanned

wrench. A retaining plate 189 is bolted to the breaker bar 92 (by bolts not shown) and a helical compression spring 190 surrounds the plunger 183 and bears against the retaining plate 189 and a flange 191 on plunger 183. The cylinders or bushings 193 are slipped into bored holes 194 in the bar 92 and engage a tapered shoulder 195 therein, being clamped between said shoulder and the retaining plates 189. A groove 196 in the plate 189 engages a tongue 197 on bushing 193 to center the plate. Pressure enters the bushing 193 through a small hole 198 and the stroke of the plunger is indicated by dotted lines at 199. 15 By this modified form of breaker I am enabled to obtain a longer stroke of the plungers for the same height of cut or conversely a less height of cut for the same stroke of the plungers. A compression spring may also be employed instead of a tension spring and the arrangement of the spring is less complicated than that shown in Fig. 5.

Assuming for the moment a source of pressure which will be described later, when the 25 lower lump is ready to be broken down the parts are positioned as shown in Fig. 1 and pressure applied first to the middle four breaker cylinders, as will be described in detail later. This breaks down the middle portion of lump 40 which falls on plate 115. After this middle portion of lump 40 has been broken down the remaining breaker cylinders are operated to break down the remainder of the lump 40.

30 During the breaking down of lump 40 the reaction from the pressure of the breaker cylinders is transferred to the roof of the mine by a series of swinging struts 116 of which six are shown although there may be one for each breaker cylinder.

The struts 116 are mounted on a shaft or otherwise hinged to the upper chain frame C so that they hang vertically over the breaker bar 92 as shown. A threaded shank 118 permits of adjustment to suit the variously adjusted positions of frame C.

45 After the lower lump 40 is broken down the ground wheels B are operated at their slow speed to feed the machine forward and 50 advance the chains 33, 34 and 35. When the machine has advanced 6" (as at present designed) the upper lump 39 is ready to break down.

As shown in Fig. 1 the breaker bar 92 is 55 18" in rear of the position it assumes when breaking down lump 39. Six inches of this amount is obtained by the advance of the machine and the remaining foot by the forward stroke of piston 96 and rod 97 which moves the breaker bar 92 forward twelve inches on the guides 93.

60 During this shift a rope or chain 119 having one end secured to a bracket 120 mounted on rod 97 and passing over pulleys 121 and 65 122 to a clamp 123 secured to one of the swing-

ing struts 116, operates to swing the struts 116 away from the face of the coal to an inclined position indicated in dotted lines at 124.

Pressure may now be applied to the breakers G to break down the upper lump, the same being preferably applied first at the center of the lump and lastly at the ends of the lump as described for the lower lump 40.

70 It will be understood that the lumps 39 or 40 do not fall as a whole nor would they do so probably even if all the breakers G were simultaneously operated. As coal is a very brittle material the effect of the pressure is to cause cross cracks in various directions through the mass and thus separate the whole 80 lump 39 into portions of various sizes depending on the characteristics of the coal, the pressure and other factors.

It is possible that the lump 40 being of slight depth might break off as one piece but 85 this possibility is avoided by breaking out the middle portion first. The lump coal as broken down falls on the plate 115 which forms part of the chain frame E.

90 The main conveyer comprises two close pitch roller chains 125 with connecting bar flights 126. The chains 125 at their forward ends pass over sprockets 127 on a shaft 128 located below the plate 115 and above the plate 129, the shaft 128 being driven by the 95 chains 125.

100 Bevel gears 130 on the ends of shaft 128 drive bevel gears 131 on short shafts 132. A chain 133 working in a slot 134 in plate 115 drives a shaft 135 which in turn drives four short chains 136 also working in slots 137 in plate 115 and passing over an idler shaft 138, this construction being duplicated to form 105 two sets of wing conveyors moving towards the main conveyor. The chains 133 and 136 extend through their slots above the top of plate 115 and about $1\frac{1}{4}$ " and any coal falling on them is dragged to the main conveyor and taken up the incline by the flights 126.

110 The chains 125 at their rear ends pass over a head shaft 138 mounted on frame A and the coal is delivered either to an auxiliary loading conveyor (not shown) which delivers it to pit cars, or the main conveyor may be extended rearwardly of the machine to deliver directly into the pit cars.

115 The flights 126 ride on the conveyor plate 180 on which the coal also is dragged. The return strands of chains 125 have their flights 126 bearing on a pair of guide bars 181. Side plates for the conveyor trough are shown at 182. The forward end of the conveyer is supported on the lower cutter frame E, and the rear end of the conveyer is supported from the frame A by means of supports 183 and 184 extending from frame A up to the 120 guide bars 181, the side plates 182 and conveyor plate 180 being supported from the bars 181 by means of brackets 185.

125 The main conveyor chains 125 are driven 130

5 by sprockets 139 on a shaft 140 mounted on frame A and driven by spur gears, and a short chain drive which need not be described in detail, from a small motor 141 mounted on frame A.

A second small motor 142 drives a pair of small hydraulic pressure pumps 143 and 144 located under the chain drive motors 62 and 63 respectively.

10 By having two pumps a more convenient utilization of available space is effected and in case of the failure of either pump the other can be used alone.

15 A further important feature of my improved machine is the hydraulic lifting turntable H which is clearly shown in Figure 3.

The lifting cylinder 145 is formed integral with a rigid hollow cross beam 146 which is strongly bolted to frame A. A steel plunger 20 161 having a cup leather 147 and retaining ring 148 is also provided with a bottom flange 149 which is bolted to the upper member 150 of a two piece turntable. The lower turntable member 151 is loosely connected to the 25 upper member 150 by a central bolt 152 and a ring of balls 153 transfer the weight from the upper to the lower member.

Above the main cylinder 145 there is a small re-setting cylinder having a piston 155 30 mounted on a piston rod 156 which passes through a stuffing box 157 and gland 158 and has its lower end screwed into the main plunger 161. The rod 156 extends upwardly through a loose cover 159 and at its upper 35 end has a slot passing through it in which a retaining key 160 is placed to hold the turntable off the ground.

By means of the turntable H the machine 40 may be raised so the ground wheels B clear the ground, when the machine may be swung to any desired angle. The turntable H may also be used to merely raise the machine in order to put inclined rails under it to obtain a sudden change of vertical direction, or to 45 place plates or rails under the ground wheels B in order to skid the machine sidewise, or in order to conveniently change the bits in the lower chain 33.

Having now described the several hydraulically operated elements I will complete the 50 description of the hydraulic devices by reference to Fig. 8 which shows them all diagrammatically.

The pumps 143 and 144 have their pressure outlets passing through stop valves 162 and 163 respectively, which connect with a main pressure line 164 which extends to three four-way valves 165, 166 and 167.

Each of these three latter valves has a pressure inlet connected to line 164, a return outlet connected to line 168 which leads back to the tank 146, and two pressure outlets.

From the valve 165 a pressure line 169 leads to a manifold 170 connecting a number 65 of the breakers G, say the four middle ones.

From the same valve a second pressure line 171 leads to a manifold 172 connecting the breakers G at either side of the middle ones. By manipulation of the valve 165 pressure may be obviously passed through either line 70 169 or line 171 at will.

From valve 166 a pressure line 173 leads to the re-setting turntable cylinder 154 and also a second line 174 leads to the main lifting cylinder 145. By means of valve 166 75 pressure may be directed to either cylinder at will.

From valve 167 a pressure line 175 leads to the rear end of the breaker bar shifting cylinder 94 and a second pressure line 176 80 leads to the front end of the same and by operating the valve 167 the breaker bar 92 may be advanced or retracted at will.

A pipe 177 connects the pressure line 164 and the tank 146 and this line contains a 85 safety valve 178 set to the maximum pressure desired, any excess being passed back to the tank. The pipes 169 and 171 being connected to a moving member (the breaker bar 92) must be provided with some form of flexible 90 connection such as swing elbows, telescopic joints or other well known device for the purpose.

The operation of my improved machine 95 has been sufficiently indicated by the above description except as to its speed and tonnage. As shown the entry being driven is five feet six inches high by an average of about ten feet four inches wide, or an area of 56 sq. ft. Since coal in the solid weighs upwards of 80 lbs. per cubic foot there will be about 4500 lbs. of coal removed per foot advance of the machine. There are over 15000 chain undercutting machines in use and it is accurately known how fast such chains will 100 cut. From this experience the following cycle of operations for my improved machine 105 is predicated.

1st minute—machine advance 6".

2nd minute—lower lump broken down.

110

3rd minute—machine advances 6" more.

4th minute—upper lump broken down.

If therefore, there are no delays in operation and no shortage of mine cars the machine can mine and load 2 1/4 tons every four 115 minutes, or at the rate of 15 feet advance per working hour. At present this is a rate of speed which has only been dreamed of.

The above relates to entry driving, but my improved machine can also be used in room 120 work as follows:

Fig. 7 represents a sectional plan of a portion of a coal mine with the lid off showing a method of using my machine in working out rooms. The shaded portions of the diagram 125 represent the unmined coal and the white spaces show where the coal has been taken out. By this method the machine is used to take successive slices off the sides of the room until the full width is mined. It is 130

practically a long wall system on a limited scale.

Referring to Fig. 7, 201 and 202 show a pair of parallel entries both driven preferably before the rooms are started, although 202 may be driven in another manner as will appear later. 203, 204, 205 and 216 show a series of rooms, necks or passages connecting the haulage way 201 with the rooms. 206 represents the mining machine, 207 represents the turntable H on the machine and the dotted circles 208 represent the circle in which the machine may be swung on the turntable.

15 In room connecting with neck 203 the machine 206 is shown making a first cut 209, in room connecting with neck 204 the machine is making a second cut 210 and in room connecting 205 the machine is making a third or 20 finishing cut 211. A completed room is shown at 212.

The machine represented in Fig. 7 is assumed to be of smaller size than the entry driving machine previously described. The 25 dimensions assumed in Fig. 7 are as follows:

Machine 22 ft. long—cuts 7' wide.

Entries 9 ft. wide—rooms 21 feet wide.

Ribs between rooms 12 feet thick.

This is merely a matter of convenience to 30 fit the illustration to present mining practice, as it is obvious that a wider machine may be used and only two cuts made in each room.

At 213 I have shown the machine 206 swung on the turntable 207 ready to pass into 35 another room. This passage is made through the remaining portion of entry 202, which by cutting out the rooms as shown, has become merely a series of "breaks through" connecting the rooms. It will now be seen that 40 this entry could be driven after the rooms are started as a series of "breaks through."

Before starting the machine to work in a room it is necessary to mine out a starting place for the machine as shown at 214 which 45 may be done in any desired manner.

It is preferable to drive the entries 201 and 202 at the same time cutting a break through as 203 at intervals, for in this way proper ventilation is secured. It will be noted that the 50 entry 201 is the haulage way through which the coal mined is removed, and that the machine 206 never enters the entry 201.

The entry 202 is prepared especially as a 55 passage way for the transfer of the machine 206 from room to room although it may also be used for other purposes. In practice it would usually be better to leave a group of unmined rooms ahead of each machine instead of having the machines in adjacent rooms as 60 shown. However, if it is desired to rapidly mine out the coal in any portion of the mine the machines can be used as close together as may be desired, since by means of the entry 202 they can pass a room in which another

machine is working and so go by each other 65 without interference.

The room and pillar system of mining shown in Fig. 7 is in very extensive use practically excluding all other methods in the Pittsburgh district, and while it may be 70 found of advantage to modify this system to suit the new characteristics introduced by my improved machine, there will probably always be mines in which it is desired to use the present system or nearly so. This is 75 especially true of partly worked out mines where it would be impossible to change the existing layout entirely, and for such places the method of working shown in Fig. 7 has been devised.

80 By means of the hydraulic turntable H, I am enabled to swing the machine to pass through entry 202 as shown, and also to lift it so that plates or skids may be set under it in order to slide it sideways to position it 85 for the next cut.

By working out the rooms in parallel slices the machine is worked a greater proportion of its time than when working across the whole face of the room by successive settings. 90

As an illustration of what may be accomplished by this method if the rooms are 300 feet long (the machine cut portion) and the machine makes three parallel cuts and advances at an average rate when cutting of 95 fifteen feet per hour, the rooms could be completely mined out in sixty hours. There would be two side shifts to position machine for its next cut and one transfer from the previously mined room which usually would not aggregate more than two hours or a total of sixty-two hours per room. With present methods the completion of a room is a matter of months.

If the machine was wider (say eleven feet) 105 or the room was narrower and only two cuts were made lengthwise of the room the time required for a 300 foot room would be about forty-two hours.

A further advantage of this system is that 110 the width of the cut made by the machine need never be greater than the unsupported roof will safely stand. When the second and third cuts are being made a line of posts can be set as the machine advances and outside 115 of the path of the machine so they will not be interfered with when the machine is withdrawn.

Where draw slate is present the slate from 120 the first cut can be "gobbed" in the previous- ly mined room and the slate from the second and third cuts gobbed in the first and second cuts respectively. In this case the first cut would be made on the opposite side of the room from the room neck instead of on the same side as shown, so as to leave the third 125 cut clear to be used as a haulage way for the removal of the ribs.

The combined effects of the above method of working and the tonnage capacity due to the special features of the machine itself make possible results as to speed of working and consequent reduction of mining cost not hitherto obtainable.

I claim as my invention:

1. In a mining machine, a frame, a cutter bar carried thereby, a second cutter bar also carried by said frame and being wider than said first cutter bar, means for feeding the cutter bars into the coal, and dislodging means carried by said frame and operating in the kerf cut by the wider cutter bar for dislodging the coal between the kerfs cut by the two cutter bars.

2. In a mining machine, a frame, and three horizontal cutter bars carried thereby at different levels, the middle cutter bar being wider and deeper than the others, means for feeding the cutter bars into the coal, and dislodging means carried by said frame, and operating in the kerf cut by the middle cutter bar for dislodging the coal at either side of the middle kerf and between the top and bottom kerfs.

3. In a mining machine, a frame, and three horizontal cutter bars carried thereby at different levels, the middle cutter bar being wider and deeper and further advanced than the others, means for feeding the cutter bars into the coal, and dislodging means carried by said frame and operating in the kerf cut by the middle cutter bar, for dislodging the coal at either side of the middle kerf and between the top and bottom kerfs.

4. In a mining machine, the combination of a frame and continuously operatable means carried thereby for cutting three horizontal slots in the coal at different levels, the middle slot being deeper than the others; and intermittently operatable means carried by said frame and operating behind said middle slot cutting means to break down the coal above and below said middle slot, whereby the cutting mechanism can be operated continuously to cut the slots to the desired depth and the breaking down mechanism can be operated at desired intervals to break down the coal.

5. In a mining machine, a frame, and means carried thereby for cutting a pair of slots in the coal in combination with means intermittently operatable for exerting a steady pressure against the sides of one of said slots to break down the coal between the slots, said pressure exerting means being located in one of said slots behind the corresponding cutting means.

6. In a mining machine, a frame, and means carried thereby for cutting a pair of slots in the coal in combination with hydraulically operated means carried by said frame and operatable at will for intermittently applying pressure between the sides of one of

said slots to break down the coal between the slots, said hydraulically operated means being located behind one of said slot cutting means.

7. In a mining machine, a frame, and means carried thereby for cutting a pair of slots in the coal in combination with a hydraulic cylinder carried by said frame and provided with a pair of opposed plungers operable at will for intermittently applying pressure to the sides of one of the slots to break down the coal between the slots, said cylinder being located behind one of the said slot cutting means.

8. In a mining machine, a frame, and means carried thereby for cutting a pair of slots in the coal in combination with a series of hydraulic cylinders for intermittently applying pressure between the walls of one of the slots to break down the coal between the slots, said cylinders being operatable at will to break down the coal when the slots have been cut to a desired depth.

9. In a mining machine, a frame, and means carried thereby for cutting a pair of slots in the coal in combination with a hydraulic cylinder operable at will and located in one of said slots behind one of the cutting devices, to break down the coal between the slots and a pressure pump carried by said frame and co-operating with said cylinder to supply the cylinder with pressure.

10. In a machine for breaking coal out of the solid, a frame, means carried thereby for cutting a pair of slots in the coal, a hydraulically operated device mounted on said frame and positioned so as to follow a cutting device into the slot cut thereby, and means for operating said hydraulic device to break down the coal between the slots when the same have been cut to the desired depth.

11. In a mining machine, a frame, and means carried thereby for cutting a pair of slots in the coal, in combination with a breaker bar provided with intermittently operatable extensible hydraulic plungers, said breaker bar being located in one of the said slots behind the corresponding cutting device to break down the coal between the slots when the same have been cut to a desired depth.

12. In a machine for breaking coal out of the solid, a frame, and means carried thereby for cutting three horizontal slots at different levels, in combination with a breaking device acting at the level of the middle slot and arranged to exert pressure upon either the mass above or below said slot, and means for shifting said breaking device forward and backward to locate the line of cleavage.

13. In a machine for breaking coal out of the solid, a frame, and means carried thereby for cutting three horizontal slots at different levels, in combination with a breaking device acting at the level of the middle slot and arranged to exert pressure upon either the mass

- above or below said slot, and a fluid pressure cylinder for shifting said breaking device to locate the line of cleavage.
14. In a mining machine, a main frame, means carried thereby for making an undercut and an uppercut, a chain for making a middlecut, a chain frame for said chain carried by said main frame, and a breaking device mounted on said chain frame.
15. In a mining machine, a main frame, means carried thereby for making an undercut and an uppercut, a chain for making a middlecut, a chain frame for said chain carried on said main frame, guides on said chain frame, a breaking device mounted on said guides, and means for shifting said breaking device along said guides to locate the line of cleavage.
16. In a mining machine, a frame, means carried thereby for cutting three horizontal slots in the coal at different levels in combination with a breaking down device, arranged to alternately break down the coal above and below the middle slot.
17. In a machine for breaking coal out of the solid, a frame, means carried thereby for cutting three horizontal slots in the coal at different levels, the upper and lower slots forming clearances for the movement of the coal required to break it, and the middle slot providing surfaces upon which a dislodging pressure may be applied, in combination with a fluid pressure device for breaking the masses above and below said middle slot away from their native bed, means for advancing the cuts, and means for positioning the breaking device to alternately break down the upper and lower masses as the cuts are advanced.
18. In a machine for breaking coal out of the solid, a frame, means carried thereby for cutting three horizontal slots in the coal at different levels, the upper and lower slots forming clearances for the movement of the coal required to break it, and the middle slot providing surfaces upon which a dislodging pressure may be applied, in combination with a fluid pressure device for breaking the masses above and below said middle slot away from their native bed, and a strut hinged to the support for the upper cutting mechanism, and arranged to transfer the reaction of the breaking device to the roof of the mine when breaking down the lower mass.
19. In a mining machine, the combination of a frame, upper, lower, and intermediate cutting mechanisms carried thereby for cutting horizontal slots in the coal, a breaking device for breaking down the lumps between the slots, and a strut hinged to the support for the upper cutting mechanism and adapted to engage the breaking device and the roof of the mine.
20. In a machine for breaking coal out of the solid, a frame, means carried thereby for cutting three horizontal slots in the coal, to prepare the same for breakage, a breaking device mounted on said frame and arranged to break down either the upper or lower mass, means for shifting the breaking device to alternately break down the upper and lower masses, a hinged strut arranged to transfer the reaction of the breaking device to the roof of the mine when breaking down the lower mass, and a connection between the said shifting device and the said strut whereby the strut swings into position over the breaking device when the lower mass is to be broken down and is pulled up out of the way by the movement of the shifting device when the upper mass is to be broken.
21. In a machine for breaking coal out of the solid, a frame, means carried thereby for cutting three horizontal slots in the coal, to prepare the same for breakage, a breaking device mounted on said frame and arranged to break down either the upper or lower mass, said breaking device comprising a breaker bar provided with a series of hydraulic breakers, means for shifting the breaker bar to alternately break down the masses above and below the middle slot, a series of hinged struts hanging vertically over the breakers when they are in position to break down the lower mass, and a connection between said shifting means and said struts to swing the latter out of the way when the upper mass is to be broken.
22. In a machine for breaking coal out of the solid, a frame, means carried thereby for cutting a pair of slots in the coal, one of said slots providing clearance for the movement of the mass between the slots when being broken off, and the other slot providing space for the introduction of a breaking device; a fluid pressure device operating in one of the slots to break off the mass of coal between the slots, and means whereby the pressure exerted by said pressure device can be applied to one portion of said slot before the others.
23. In a machine for breaking coal out of the solid, a frame, means carried thereby for cutting a pair of slots in the coal, one of said slots providing clearance for the movement of the mass between the slots when being broken off, and the other slot providing space for the introduction of a breaking device; a series of pressure exerting units arranged to operate in one of the slots to break off the mass between the slots, and means whereby certain of said units are made to act before the others.
24. In a machine for breaking coal out of the solid, a frame, means carried thereby for cutting a pair of slots in the coal, one of said slots providing clearance for the movement of the mass between the slots when being broken off, and the other slot providing space for the introduction of a breaking device, a breaking device comprising two sets of hy-

draulic breakers, a pump to supply pressure to the breakers, and valve mechanism for controlling the application of the pressure to either set of breakers at will.

5 25. In a machine for breaking coal out of the solid, a frame, means carried thereby for cutting a slot in the coal to permit of its deflection for breakage, means also carried by said frame for making an opening in the coal

10 to receive a pressure exerting device, and means operable independently of the movement of the cutting device carried by said frame, and arranged to enter said opening and to exert pressure to break down the coal.

15 26. In a machine for breaking coal out of the solid, a frame, means carried thereby for cutting a pair of slots in the coal, one of said slots providing clearance for the movement of the mass between the slots when being

20 broken off, and the other slot providing space for the introduction of a breaking device, a fluid pressure device carried by said frame and arranged to operate in one of said slots behind the cutting device to break off the

25 mass of coal between the slots, and means for operating the fluid pressure device when desired independently of the action of the cutting means.

27. In a mining machine, a frame and 30 three horizontal cutting chains carried thereby at different levels, the upper and lower of said chains operating in one direction, and the middle chain operating in the opposite direction, whereby the side thrust 35 of the upper and lower chains is counteracted by that of the middle chain.

28. In a mining machine, the combination 40 of a frame and four horizontal cutting chains carried thereby at different levels, the upper and lower chains being at the top and bottom of the machine and operating in one direction, and the other two chains being located between them and set close together to cut a common slot, and operating in a direction 45 opposite to that of the upper and lower chains, whereby the side thrusts of the various chains are balanced, and the cuttings from the upper and lower chains are delivered to one side of the machine, and the cuttings from the middle chains to the other side thereof.

29. In a mining machine, a main frame, an upper chain carrying frame, a lower chain carrying frame, four vertical screws carried 55 by said main frame and vertically adjustable with respect thereto, said screws supporting the upper and lower chain carrying frames, means for adjusting the upper chain carrying frame on said screws, and cutting chains 60 mounted on said chain carrying frames.

30. In a mining machine, the combination 65 of a frame, means carried thereby for making an incision in the material, and means lying within the boundary of the incision means and co-acting therewith for exerting

pressure on the walls of the incision to break out the material, said pressure exerting means being operable independently of the movement of the incision making means.

31. In a mining machine, the combination 70 of a frame, means carried thereby for making an incision in the material, and means attached to the incision means, and lying behind the same and within the boundary of the same, and arranged to exert pressure on 75 the walls of the incision to break out the material, said pressure exerting means being operable independently of the movement of the incision making means.

32. In a mining machine, the combination 80 of a frame, a cutting chain carried thereby, and means lying within the boundary formed by the cutting chain and positioned within the kerf cut by the said chain, for breaking out the material being mined, said breaking 85 means being operable independently of the movement of the cutting chain.

33. In a mining machine, the combination 90 of a frame, means carried thereby for cutting a pair of slots in the material being mined, and a fluid pressure device carried by said frame and operating in one of said slots to break down the mass of material between the slots.

34. In a mining machine, the combination 95 of a frame, means carried thereby for making a pair of incisions in the material being mined, and fluid pressure means carried by said frame and positioned in the lower incision and arranged to exert pressure on the 100 walls thereof to break the material upwardly.

35. In a mining machine, the combination 105 of a "cutter bar" comprising a kerf cutting chain with supporting means and driving means for the same; and a hydraulic device mounted on the cutter bar within the kerf 110 cut by the chain and behind the same for exerting pressure on the sides of the kerf to break down the coal.

36. In a mining machine, a frame, cutting 115 mechanism for making an initial incision in the coal mounted on said frame, said mechanism being provided with movable cutting edges, means lying behind the incision cutting mechanism, and arranged to follow the same into the incision and to exert pressure on the walls thereof to break out the coal; said pressure exerting means being normally stationary with respect to the frame of the machine, and conveying means at the rear of said 120 cutting and said breaking means to receive the coal and convey it away.

37. In a mining machine, the combination 125 with the two independent cutter chains arranged to travel in horizontal planes and to simultaneously produce two parallel horizontal kerfs across the face of the coal, of means following immediately behind the active cutters of the upper chain and arranged to exert a downward pressure on the coal below it to 130

dislodge it, and means to control the pressure exerting means.

38. In a mining machine, the combination with the two independent cutter chains arranged to travel in horizontal planes, and to simultaneously produce two parallel horizontal kerfs across the face of the coal, means following immediately behind the active cutters of the upper chain and exerting downward pressure on the coal to dislodge it, devices to control the pressure exerting means, and means behind the pressure devices and inside of the coal face to receive and remove that which is dislodged.

15 39. In a mining machine, the combination with the two independent cutter chains arranged to travel in horizontal planes and to simultaneously produce two parallel horizontal kerfs across the face of the coal, of vertically acting hydrostatically actuated breaking down devices arranged immediately behind the active cutters of the upper chain and adapted to exert pressure upon the over-cut coal and devices to actuate and control the pressure exerting means.

20 40. In a mining machine, the combination of a horizontally projecting arm with a cutter chain traveling horizontally around said arm to form a kerf across the face of a mine wall at the base thereof, a simultaneously operating chain cutter adapted to form a kerf across the face of a mine wall above and parallel to the first mentioned kerf, breaking means carried with and following immediately in the path of the upper cutting devices to break down the severed sections, and simultaneously operating conveying devices connected to move with said cutting and breaking devices to receive and remove the coal, and having a receiving section situated in transverse lines inside of the coal face.

25 41. In a mining machine, the combination of a cutter comprising a horizontally extending arm and a cutter chain traveling horizontally around said arm, to form a kerf across the face of a mine wall at the base thereof, a simultaneously operating chain cutter adapted to form a kerf across the face of the mine wall above and parallel to the first mentioned kerf, breaking means carried with and following immediately in the path of the upper cutting devices to break down the severed sections, and simultaneously operating conveying devices arranged to travel on the lines along which the breaking means travel bodily to receive the coal falling backward therefrom.

30 42. In a mining machine, the combination with a horizontal kerf-cutter comprising a horizontal cutter-frame with an opening extending transversely therethrough for the passage of material dislodged above said kerf-cutter, breaking mechanism extending into the kerf cut by said kerf-cutter in position to break down material adjacent said kerf-

cutter, and means for operating said breaking mechanism.

43. In a mining machine, the combination with a plane kerf-cutter comprising a cutter chain traveling on a cutter frame having a free and unobstructed opening extending transversely therethrough for the passage of material dislodged above said kerf-cutter, breaking mechanism carried by said cutter frame at one side of said opening therein and in position to move along the kerf cut by said kerf-cutter, means for operating said breaking mechanism to dislodge material adjacent said kerf, and means for operating said kerf-cutter including feeding movement thereof in its own plane.

44. In mining apparatus, the combination with an under-cutting kerf cutter comprising a plane horizontal cutter frame, of a conveyor inclined upwardly from a horizontal portion within the boundary of said cutter frame, a horizontal kerf-cutter above said undercutter, and comprising a cutter frame with a cutter chain thereon, means for operating said kerf cutters including feed thereof as a unit and breaking mechanism within the boundary of the cutter frame of said upper kerf cutter in position to move into the kerf cut by the latter.

45. In a mining machine, the combination with a supporting frame, of a chain kerf-cutter mounted thereon in position to cut a kerf in a general horizontal direction in an elevated position relative to the floor of the mine chamber, and expandable mechanism carried by said kerf-cutter in position to exert pressure on the walls of the kerf to dislodge coal below said kerf.

46. In a mining machine, the combination with a supporting frame, of a flat chain-cutter adapted to cut a plane horizontal kerf in an elevated position, and pressure-exerting means adapted to follow into the kerf and exert pressure on the walls thereof independently of the bodily movement of said chain kerf-cutter to cause the coal below said kerf to be dislodged from the mine vein.

47. In a machine for breaking coal out of the solid, a frame, cutting means carried thereby for forming an opening in the coal to permit of its deflection for breakage and for also making an opening in the coal adapted to receive a pressure-exerting device, a support held by said frame and projecting directly inward therefrom to have its inner end part directly support the cutting means, and a vertically movable pressure-exerting device also carried by said support and normally stationary thereon and adapted to be vertically moved relatively thereto on vertical lines which are within the outlines of the path of the cutter and which pass through said support.

48. In a machine for breaking coal out of the solid, a frame, means carried thereby for

cutting two co-related openings in the material being mined, a fluid actuated pressure-exerting device, means for supplying a pressure fluid to the said pressure-exerting device, and a bar-like support carried by said frame and holding in common both said cutting means, said pressure device and said fluid supplying means, the pressure device being arranged to follow the cutting means into an opening such as aforesaid in the coal and to be moved vertically through the lower horizontal planes of said support on lines perpendicular to the lines of advance of the cutting means.

49. In a machine for breaking coal out of the solid, a frame, cutting means for forming two co-related openings in the coal, one of said openings providing clearance for downward movement of the mass, between the openings when broken off, the other opening providing space for the introduction of a breaking device, a support held by said frame and carrying said cutting means and provided with a duct for pressure fluid, a fluid pressure breaking device also carried by said support behind the cutting means, and manually controlled devices for causing said fluid pressure breaking device to operatively move relatively to said support independently of the action of the cutting means.

50. In a mining machine, the combination with a plane kerf-cutter comprising a cutter-frame and an endless traveling chain cutter mounted thereon, of a pressure-exerting device carried by said cutter-frame within the boundary of the chain cutter and comprising relatively telescoping members with a spring enclosed thereby.

51. In a mining machine, the combination

with a supporting frame, of a plane kerf-⁴⁰ cutter mounted thereon in position to cut a kerf in a general horizontal direction, said kerf cutter comprising a flat cutter-frame and an endless cutter-chain mounted thereon, and an expansible pressure-exerting device ⁴⁵ mounted on said flat cutter-frame in position to exert pressure on the walls of the kerf produced by said kerf-cutter, said pressure-exerting device comprising relatively telescoping members with an intermediate ⁵⁰ spring.

52. In a mining machine, the combination of a plane kerf-cutter comprising a flat cutter-frame and an endless cutter-chain mounted thereon, an expansible pressure-exerting ⁵⁵ device mounted on said cutter-frame within the boundary thereof and comprising pressure-exerting plungers movable in opposite directions each relatively to said cutter-frame, and a spring between said plungers. ⁶⁰

53. In a mining machine, the combination with a supporting frame, of a plane kerf-cutter mounted on said frame in position to cut a horizontal kerf and comprising a cutter frame and an endless chain-cutter, and ⁶⁵ pressure-exerting mechanism supported within the boundary of said cutter-frame in position to enter the kerf cut by the kerf-cutter, said pressure-exerting mechanism comprising pressure-exerting plungers movable in ⁷⁰ opposite directions relatively to each other and each relatively to said cutter-frame, and a spring extending between the plungers in position to act thereon to move each relatively to said cutter-frame. ⁷⁵

In testimony whereof I hereunto affix my signature.

WALTER W. MACFARREN.
